Primary Examiner — Keli L Hill*Assistant Examiner* — Sara S Sahneh(74) *Attorney, Agent, or Firm* — Weide & Miller, Ltd.(57) **CLAIM**

The ornamental design for a one-handed pipe wrench, as shown and described.

DESCRIPTION

FIG. 1 is a front, top, right perspective view of a one-handed pipe wrench showing the new design;

FIG. 2 is a rear, top, left perspective view of the one-handed pipe wrench shown in FIG. 1;

FIG. 3 is a top view of the one-handed pipe wrench shown in FIG. 1;

FIG. 4 is a left-side view of the one-handed pipe wrench shown in FIG. 1;

FIG. 5 is a front view of the one-handed pipe wrench shown in FIG. 1;

FIG. 6 is a right-side view of the one-handed pipe wrench shown in FIG. 1;

FIG. 7 is a rear view of the one-handed pipe wrench shown in FIG. 1; and,

FIG. 8 is a bottom view of the one-handed pipe wrench shown in FIG. 1.
